UNITED STATES PATENT OFFICE.

WILLIAM JOHN VINCENT, OF CARDIFF, WALES.

ROTARY PUMP AND MOTOR.

1,135,414.

Specification of Letters Patent. Patented Apr. 13, 1915.

Application filed March 7, 1914. Serial No. 823,166.

To all whom it may concern:

Be it known that I, WILLIAM JOHN VINCENT, of Cardiff, in the county of Glamorgan, Wales, have invented certain new and useful Improvements in Rotary Pumps and Motors, of which the following is a specification.

This invention relates to improvements in rotary pumps and motors and has reference 10 to pumps and motors having radial bodily rotatable cylinders whose pistons coöperate with eccentrics or cam paths so that the working fluid is received into the outer ends of the cylinders during one part of the revolution of the cylinder body and expelled 15 from those cylinders during the other part of the revolution.

The present invention comprises a particular construction of such apparatus designed 20 for simplicity of manufacture and efficiency of operation. A primary feature of this construction consists in forming the piston which operates in one cylinder integral with or positively connected to the piston operating in the cylinder diametrically opposite. That is to say, that the rotating cylinder body is provided with an even 25 number of cylinders diametrically opposite each other and the diametrically opposite 30 pistons are connected together and move in unison so that the suction stroke of one piston corresponds exactly to the delivery stroke of the opposite piston connected to it and moving in unison with it. The reciprocation 35 of the pistons is derived from a roller or rollers mounted eccentrically to the axis of rotation of the cylinder body which is of course the primary axis of the machine and it will be understood that the stroke of 40 the pistons will depend upon the degree to which the one axis is eccentric to the other and in order to provide for variation of delivery and reversal of flow I propose to provide means for varying this eccentricity in 45 order to vary the stroke of the pistons. This variation of stroke may be effected by bodily sliding the eccentric rollers relative to the primary axis of the machine or by providing these rollers on compound eccentrics so 50 that the rotation of one eccentric about the other will cause variation of the eccentricity. It will be understood that if provision is made for adjustment of the eccentric center to either side of the primary axis of the machine 55 reversibility can also be provided for with the cylinder body rotating always in

one direction. The cylinders can all be arranged in the same plane or more than one row of cylinders can be provided in which case the cylinders of one row or plane may 60 be staggered in position relative to those in the other row or plane.

In the accompanying drawings I have illustrated various embodiments of my invention, Figure 1 being an end sectional elevation of a fixed stroke machine constructed in accordance with my invention. Fig. 2 is a sectional view thereof on line A—A of Fig. 1. Figs. 3 and 4 are similar views of a very simple form of fixed stroke machine wherein 70 only one pair of cylinders are employed. Fig. 5 is a transverse sectional view of a machine showing two rows of cylinders operating in conjunction with common suction and delivery chambers. Fig. 6 is a sectional 75 view thereof on line B—B of Fig. 5. Fig. 7 is a transverse section illustrating a machine very similar to that shown by Figs. 1 and 2 but provided with means whereby the stroke of the pistons can be varied so as to provide 80 for variation of delivery and reversibility of flow. Fig. 8 is a sectional view thereof on line C—C of Fig. 7. Figs. 9 and 10 are transverse sectional and elevational views respectively illustrating a modified method by 85 means of which the stroke of the pistons may be varied.

Referring to these drawings and particularly to Figs. 1 and 2 the numeral 1 designates an outer casing divided into two parts 90 by some suitable diaphragm or partition such as the bridges 2 and associated with each of these parts of the casing I provide a pipe or port one of which 3 operates as the suction or inlet and the other 4 the delivery 95 or outlet pipe or port. It will of course be understood that these inlet and outlet pipes or ports are reversible in function if the direction of rotation is reversed. Mounted to rotate centrally within this casing I provide 100 a cylinder body or rotor 5 in which diametrically opposite cylinders 6 are provided. In the machine shown in Figs. 1 and 2 four cylinders are provided. In this case two pistons structures 7 are provided, each piston 105 structure having pistons at each end as shown. One of these pistons structures can be composed of a single casting with its center or trunk 8 recessed or slotted transversely as at 9 so as to permit of the center 11 or trunk of the other piston structure passing through. The other piston structure

would be constructed in two parts, one of which would carry the trunk and in assembling the machine the one piston structure would first be inserted with the piston ends located in their cylinders and the one portion of the other piston structure would then be inserted with the trunk portion located in the recess or slot provided in the other piston structure. The other portion of this second piston structure—which would preferably be the fourth piston—would then be attached to the trunk by means of a set screw or set screws 10 or the like. Mounted eccentrically relative to the primary axis of the machine I provide a steel or other suitable pin 11 which extends approximately half way across the machine and is thus contained within recesses in the piston structure as shown in the drawings. Upon this pin 11 I mount rollers 12 and 13, the inner of which rollers has an end wall 14 which incloses the end of the pin 11 and is provided with a sleeve 15 upon which the other roller 12 is mounted so that the two rollers are mounted upon the same axis. The pin 11 is preferably bored right through, the opening 16 thus provided serving to take some form of lubricant, and seeing that the end of this opening is closed by the wall of the inner roller the lubricant is forced to circulate around the pin, and radial bores such as 17 proceeding from the central bore may be provided to conduct the lubricant to the desired positions. Each of the rollers 12 and 13 aforesaid co-operates with one or other of the pistons, clearances 18 being provided to insure that each of the piston structures only comes into contact with its own roller. The separate roller for each of the piston structures is provided to accommodate the differential circumferential travel of the pistons relative to the rollers due to the eccentricity. The outer cylindrical casing of the machine is of course closed by means of a circular side plate or plates. In operation assuming the machine to be in use as a pump, the cylinder body or rotor 5 is driven by means of a shaft 19 connected to it, and the co-operation of the pistons 7 with the eccentrically situated rollers aforesaid causes reciprocation of the pistons and fluid is drawn into the cylinders from one side of the casing and is expelled from the other side as will be readily understood by those conversant with this type of apparatus. In order to provide a convenient means for compensating for any wear which may tend to cause leakage past the bridges or partitions 2 in the casing 1 I propose to construct the bridges removable, and interchangeable liners indicated at 20 of thin metal may be provided so that in the case of wear these liners may be rearranged or renewed. The bridge 2 at the top of the machine is preferably given a distinct overlap as indicated at

21 so that as the cylinders pass the bridge the shock due to liquid pressure on the one side of the machine precedes the shock due to the vacuum on the other side of the machine. In the absence of this overlap the two shocks would be simultaneous and the overlap is provided in order to obviate this double shock. 70

In Figs. 3 and 4 a machine very similar to that previously described is illustrated. In these figures the numeral 22 designates the casing, 23 the bridges or partitions, 24 the inlet or suction pipe and 25 the outlet or delivery pipe. The single piston structure is indicated by the numeral 26 having a slot 27 in its trunk within which a roller 28 mounted upon an eccentrically situated pin 29 is located and it will be clear that as the rotor 30 rotates the piston structure 26 reciprocates in the cylinders 31 by reason of the eccentricity of the pin 29 and assuming the machine to be operating as a pump liquid will enter through the suction pipe 24 and be expelled through the outlet or delivery pipe 25. The driving shaft 32 is shown supported by an elbow bracket 33 in this instance. 80

In Figs. 5 and 6 I have illustrated a fixed stroke machine having two rows of cylinders 35 formed in a common rotor 36 co-operating with common inlet and outlet pipes 37 and 38 respectively. The rotor 36 is provided with a central disk 39 to which the driving shaft 40 is rigidly attached and the rotor is divided at 41 and 42 to permit of the fitting of the pistons 43 the casing parts being secured together by bolts. The end walls 44 of the casing 45 are formed with eccentric bosses 46 upon which the rollers 47, with which the piston structures 43 co-operate, are mounted. These eccentric bosses 46 are preferably provided with lubrication channels 48 and 49. The pistons are connected together as before but the yokes 50 are slotted as at 51 and in these slots the eccentric rollers 47 are located. The central disk 39 of the rotor is provided with passages 55 so that any liquid leaking past the pistons can flow freely from one side to the other. 90

In Figs. 7 and 8 I have illustrated one convenient method by means of which the stroke of the pistons may be varied to provide for variation and reversibility of delivery with constant rotation of the rotor 100 in one direction. In this case I provide a compound eccentric, the members 56 and 57 of which are rotatable relatively to each other and are mounted upon the fixed pin 58. The member 56 is connected to an internally toothed flange 59 and the member 57 is provided with teeth 60. A pinion 61 supported in the bearing 62 carried by the end wall 63 of the casing gears the two eccentric members 56 and 57 together and it 110 115 120 125 130

will be readily apparent that if the pinion 61 is rotated by means of the handle 64 or some other suitable device, the eccentric members 56 and 57 will rotate relatively to each other and the degree of eccentricity will thus be varied. In order to prevent jamming between the gear eccentrics and the gearing pinion, I provide the toothed flange 59 upon an annular disk or ring 65 and this disk or ring is capable of a radial sliding movement upon the face of the eccentric member 56 by reason of the pin 66 attached to the member 56 being located in a slot 67 in the disk or ring 65.

15 Another method of varying the degree of eccentricity between the eccentric rollers and the axis of the machine is shown in Figs. 9 and 10. In this case the pin 68 upon which the eccentric rollers are mounted in the manner before described is attached to sliding plates 69 and a screw 70 operates in a tapped opening in the outer end of the pin. By turning the screw 70 the pin 68 will be bodily moved so that its axis can be arranged at various positions in a straight line on either side of the primary axis of the machine, a slot 71 being provided in the wall 72 to accommodate the movement.

20 What I claim and desire to secure by Letters Patent is:

1. A hydraulic machine comprising a casing, a rotatable cylinder body within the casing, radial cylinders formed in said body, piston structures operating in the cylinders, 35 one of said structures consisting of a transversely slotted trunk portion having integrally formed piston heads at its ends, another of said structures having a trunk portion adapted to pass through the slot in said first mentioned trunk portion and being provided with an integral piston head at one end and a detachable piston at the other end thereof, a pin on the casing, eccentric to the axis of the cylinder body, an inner and an 40 outer roller on said pin, the inner of said rollers being provided with a sleeve upon which said outer roller rotates, said piston structures coöperating respectively with the said rollers whereby opposing piston heads 45 are caused to reciprocate in unison.

2. A hydraulic machine comprising a casing, a rotatable cylinder body within the casing, an even number of diametrically opposed radial cylinders formed in said body, 55 an even number of piston heads operating in said cylinders and being connected together in pairs, a support projecting from the casing into the rotatable cylinder body, said support being eccentric to the axis of rotation of the cylinder body, an inner and an outer roller on said support, said inner roller adapted to engage the connecting means between one of said pairs of piston heads and the outer roller adapted to engage the connecting means between another of said pairs

of piston heads whereby the piston heads of a pair are caused to operate in unison.

3. A hydraulic machine comprising a casing, a rotatable cylinder body within the casing, said cylinder body being formed with radial cylinders, pistons operating in said cylinders, removable bridges dividing said casing into suction and delivery chambers, and interchangeable metallic lining members between said bridges and the casing.

4. A hydraulic machine comprising a casing, a rotatable cylinder body within said casing, said body being provided with radial cylinders, pistons operating in said cylinders substantially oppositely disposed segmental bridges dividing said casing into suction and delivery chambers, one of said bridges being of greater circumferential length than the other of said bridges whereby the shock due to liquid pressure upon one side of the machine precedes the shock due to vacuum on the other side of the machine.

5. A hydraulic machine comprising a casing, a rotatable cylinder body within the casing, radial cylinders formed in said body, 90 piston structures operating in the cylinders each having opposing piston heads, a pin on said casing, eccentric to the axis of the cylinder body, an inner and an outer roller on said pin, one of said rollers being provided with a sleeve upon which the other roller rotates, said piston structures coöperating respectively with the said rollers whereby opposing piston heads are caused to reciprocate in unison.

6. A hydraulic machine comprising a casing, a rotatable cylinder body within the casing, radial cylinders formed in said body, piston structures operating in the cylinders, one of said structures consisting of a transversely slotted trunk portion having opposing piston heads, another of said structures having a trunk portion adapted to pass through the slot in said first mentioned trunk portion and being also provided with opposing piston heads and means adapted to engage said piston structures whereby opposing piston heads are caused to reciprocate in unison.

7. A hydraulic machine comprising a casing, a rotatable cylinder body within the casing, radial cylinders formed in the cylinder body, piston structures operating in the cylinders each having opposing piston heads, a fixed support on the casing, eccentric to the axis of the cylinder body, an inner and an outer roller on said support, said piston structures coöperating respectively with said rollers whereby opposing piston heads are caused to reciprocate in unison.

8. A hydraulic machine comprising a casing, a rotatable cylinder body within the casing, radial cylinders formed in said body, piston structures operating in the cylinders, one of said structures consisting of a trans-

versely slotted trunk portion having opposing piston heads, another of said structures having a trunk portion adapted to pass through the slot in said first mentioned trunk portion and being also provided with opposing piston heads, a fixed support on the casing, eccentric to the axis of the cylinder body, an inner and an outer roller on said support, said piston structures coöperating respectively with said rollers whereby opposing piston heads are caused to reciprocate in unison.

9. A hydraulic machine comprising a casing, a rotatable cylinder body within the casing, said cylinder body being formed with radial cylinders and bridges dividing said casing into suction and delivery chambers, said bridges being removable.

10. A hydraulic machine comprising a casing, a rotatable cylinder body within the 20 casing, said body being provided with radial cylinders, pistons operating in said cylinders, oppositely disposed means dividing said casing into suction and delivery chambers, the relative construction of said oppositely disposed means being such whereby the shock due to liquid pressure upon one side of the machine precedes the shock due to vacuum on the other side of the machine. 25

In testimony whereof I affix my signature 30 in presence of two witnesses.

WILLIAM JOHN VINCENT.
